WORK HANDLING APPARATUS

Charles A. Shaffer, Hays, Pa.

Application April 14, 1939, Serial No. 267,928

8 Claims. (Cl. 294—88)

This invention relates to certain new and useful improvements in work handling apparatus.

In work handling apparatus of the type disclosed herein and wherein cylindrical work such as steel piping or rolled cylinders of magnetic material are magnetically gripped for transportation to another part of a shop or for loading purposes, serious difficulty has been experienced by interruption in the current supply for the energization of the magnet, resulting in the dropping of the work being transported and damage thereto as well as damage to other work and possible injury to workmen. It is therefore the primary object of this invention to provide work handling apparatus embodying a lifting magnet having combined therewith pneumatically or hydraulically operated work gripping jaws so that in the event of an interruption in the source of electrical energy to the magnet, the work gripping jaws will safely transport the work.

With the above and other objects in view that will become apparent as the nature of the invention is better understood, the same consists in general of certain novel details of construction and arrangement of parts hereinafter more fully described, illustrated in the accompanying drawings and claimed.

In the accompanying drawings:

Figure 1 is a side elevational view of the work-gripping head of the work handling apparatus, the work to be transported being shown in side elevation and partly broken away and shown in section while the work-gripping head is illustrated by dotted lines in its work-gripping position.

Figure 2 is a horizontal sectional view taken on line 2—2 of Figure 1, showing operating means for the work-gripping jaws supported on the upper face of the lifting magnet.

Figure 3 is a vertical longitudinal sectional view of the work-gripping head showing the gripping jaws in their extended work-gripping positions.

Figure 4 is a vertical longitudinal sectional view, similar to Figure 3, showing the work-gripping jaws in their retracted and inoperative positions.

Figure 5 is a horizontal sectional view taken on line 5—5 of Figure 4, showing the work-gripping jaws carried by fluid operated plungers.

Figure 6 is a detailed sectional view taken on line 6—6 of Figure 4, showing a guide strip for the work-gripping jaws, and

Figure 7 is a detailed sectional view taken on line 7—7 of Figure 4, showing the anchor means

in the work-gripping head for a plunger cylinder.

The work handling apparatus is employed in connection with a derrick or shop crane, and while the same may be employed for transporting vitreous pipe, metal pipe or any tubular work, the same is primarily intended for use in the handling of rolled sheet tin for the transportation of the rolled tin from one part of a work shop to another part or for the loading thereof. The work handling apparatus comprises a work-gripping head that includes a lifting magnet 10 having marginal lugs 11 rising therefrom for the attachment of hoist chains 12 which in turn are engaged with the hook 13 of a block and tackle 14 of the type associated with a shop crane. The magnet 10 is energized through the medium of electrical devices 15 controlled in their operation by the operator of the crane.

The work-handling head includes auxiliary work-gripping devices that are effective for holding the work in the event of an interruption of electrical energy for the energization of the lifting magnet 10 and such auxiliary lifting devices include a cylinder 16 flanged at its upper end as at 17 for attachment as at 18 to the lower side of the lifting magnet 10 with the cylinder 16 of lesser diameter than the diameter of said magnet and surrounding the usual center opening 19 in the lifting magnet. The lower end of the cylinder 16 has a conical centering guide 20 detachably engaged therewith as at 21 for positioning the cylinder 16 into the bore or central opening 22 in the cylindrical work 23 as shown by dotted lines in Figure 1. The cylinder 16 has pairs of diametrically opposite longitudinally extending slotted openings 24 therein through which work-gripping jaws 25 having knurled or work-gripping faces 26 project, the work-gripping jaws 25 being shown in their retracted inoperative positions in Figures 4 and 5 and in their projected work-gripping positions in Figures 1 and 3, the operating means for the work-gripping jaws 25 being housed within the cylinder 16 and transported upon the upper face of the lifting magnet 10.

The devices within the cylinder 16 for the operation of the work-gripping jaws 25 are supported on a grill work comprising horizontal bars 27 and include a center block 28 having two horizontal crossing bores 29 arranged at right angles to each other between the upper and lower ends of the block and a vertical bore 30 extending from the upper end of the block downwardly to the intersecting point of the crossing bores 29 for communication therewith. Pairs of diametrically op-

posite cylinders 31 are anchored at their inner ends as at 32 in any suitable manner to the block 28 and each piston is further anchored in position to a frame bar 27 by means of a U-bolt 5 or shackle 33 extending downwardly over the cylinder and having the lower threaded ends of the side legs thereof extending through openings in the bar 27 for the reception of retaining nuts 35. The several cylinders 41 are respectively aligned 10 with the work-gripping jaws 25 and each cylinder 31 has a piston 36 therein backed by the usual piston cup 37 that faces a horizontal cross bore 29. Each piston 36 has a pivot lug connection 38 at its outer end with a link 39 and the outer end 15 of each link 39 has a pivot lug connection 40 with the inner side of the adjacent work-gripping jaw 25 intermediate the upper and lower ends thereof so that said jaw may move relatively to the link 39 and piston 36 to find flat contact with 20 the work 23. The work-gripping jaws 25 are guided in their movements by top and bottom flanges 41 extending inwardly from the upper and lower ends of the slotted openings 24 while horizontally disposed U-shaped guide strips 42 25 are secured as at 43 to the inner face of the cylinder 16 adjacent the upper and lower ends of the openings 24 as shown more clearly in Figure 6. As shown in Figure 5, the pivot lug connection 40 between the plunger 39 and work-gripping 30 jaws 25 include pivot pins 44 of a length to extend laterally of the cylinders 31 and each pivot pin 44 has one end of a coil spring 45 attached thereto as at 46 while the other end of the coil spring 45 is attached as at 47 to a corner of the center block 28, the springs acting to move pistons 36 and links 39 toward the inner ends of the cylinders and to retract the work-gripping jaws to their inoperative positions as shown in Figures 4 and 5.

40. While the work-gripping jaws 25 may be pneumatically or hydraulically operated, hydraulic devices are shown for purposes of illustration and include a fluid pump 48 mounted upon the upper face of the lifting magnet 10 and operated by an 45 electric motor 49 through the medium of connecting rods 50, the motor 49 receiving its energy through conductor wires under control of the operator of the crane. A pipe line 52 extends from the fluid pump 48 downwardly through the 50 central opening 19 in the lifting magnet 10 and is attached at its lower end as at 53 to the upper end of the block 28 for communication with the vertical bore 30 in said block. A check valve 54 is mounted in the pipe line 52 to prevent the 55 return flow of fluid to the pump. A by-pass pipe 55 is attached at its ends as at 56 and 57 respectively to the pipe line 52 at opposite sides of the check valve 54 and said by-pass pipe 55 has a manually operated normally spring-closed valve 60 58 therein.

65. In the use of the work handling apparatus the crane is moved and the block and tackle 14 operate to position the cylinder 16 of the work lifting head directly above the work 23, the conical head 20 guiding the cylinder 16 downwardly into the central opening 22 of the work 23, the magnet 18 being lowered into engagement with the upper end of the cylindrical work 23 as shown by dotted lines in Figure 1, and when energized with 70 electrical devices 16, the work is lifted by the magnet and transported to the desired point. When the lifting magnet 10 is engaged with the work 23, the motor 49 is then operated for operating the fluid pump 48 to cause fluid to flow 75 through the pipe 52 by way of the check valve 54

into the bores 30 and 29 in the block 28 within the cylinder 16 for moving the piston 36 toward the outer ends of the cylinders and causing the plunger 39 to move the work-gripping jaws 25 into biting engagement with the inner wall 22 5 of the cylindrical work 23. The motor 49 may have an automatic cut-out in association therewith or the motor may be of the overrunning type and will cease to operate the pump 48 after the work-gripping jaws 25 have been moved into 10 gripping engagement with the work 23. Should the supply of energy to the lifting magnet be interrupted and the magnet 10 become deenergized the work-gripping jaws 25 would still be effective for securely holding the work during transportation thereof. At the end of the journal, the work is lowered to the floor or the support, the magnet deenergized and the normally spring-closed valve 58 manually opened to allow the springs 45 to retract the pistons 36, plunger 39, and work-gripping jaws 25 and force the fluid in the inner end of the cylinders 31 and bores 29 and 30 back through the pipe 53 and through the by-pass pipe 55 to the pipe 52 for return to the pump 48 and when pressure on the valve 58 is relieved, the 20 same automatically closes and the hydraulic mechanism is automatically set for another operation of the work-gripping jaws.

From the above detailed description of the invention, it is believed that the construction and 30 operation thereof will at once be apparent, and while there is herein shown and described the preferred embodiment thereof, it is to be understood that minor changes may be made in the details of construction, such as will fall within 35 the scope of the invention as claimed.

I claim:

1. In work handling apparatus of the character described, a lifting device including a carrying member, a cylindrical head depending from the carrying member, work-gripping jaws carried by the head and horizontally movable relative thereto, hydraulically operated means for projecting the jaws including a piston and cylinder in the head for each jaw and fluid supply means 40 for the cylinders carried by the carrying member and means for retracting the work-gripping jaws to their inoperative positions within the head, the cylindrical head having slotted openings through which the gripping jaws project and 45 guide means for the gripping jaws bordering said slotted openings.

2. In work handling apparatus of the character described, a lifting device including a carrying member, a cylindrical head depending from the carrying member, work-gripping jaws carried by the head and horizontally movable relative thereto, hydraulically operated means for projecting the jaws including a piston and cylinder in the head for each jaw and fluid supply 50 means for the cylinders carried by the carrying member, means for retracting the work-gripping jaws to their inoperative positions within the head, a ported block to which each piston is attached and said fluid supply means being in communication with said ported block, the cylindrical head having slotted openings through which the gripping jaws project and guide means for the gripping jaws bordering said slotted openings.

3. In work handling apparatus of the character described, a lifting device including a carrying member, a cylindrical head depending from the carrying member, work-gripping jaws carried by the head and horizontally movable relative thereto, hydraulically operated means for 70

- projecting the jaws including a piston and cylinder in the head for each jaw and fluid supply means for the cylinders carried by the carrying member, means for retracting the work-gripping jaws to their inoperative positions within the head and a conical centering guide detachably engaged with the lower end of the cylindrical head for positioning said head within a central opening in the work being engaged. 5
5. In work handling apparatus of the character described, a lifting device including a carrying member, a cylindrical head depending from the carrying member, work-gripping jaws carried by the head and horizontally movable relative thereto, hydraulically operated means for projecting the jaws including a piston and cylinder in the head for each jaw and fluid supply means for the cylinders carried by the carrying member, means for retracting the work-gripping jaws to their inoperative positions within the head and a ported block to which each piston is attached, said fluid supply means being in communication with said ported block, and a conical centering guide detachably engaged with the lower end of the cylindrical head for positioning said head within a central opening in the work being engaged. 10
10. 4. In work handling apparatus of the character described, a lifting device including a carrying member, a cylindrical head depending from the carrying member, work-gripping jaws carried by the head and horizontally movable relative thereto, hydraulically operated means for projecting the jaws including a piston and cylinder in the head for each jaw and fluid supply means for the cylinders carried by the carrying member, means for retracting the work-gripping jaws to their inoperative positions within the head and a ported block to which each piston is attached, said fluid supply means being in communication with said ported block, and a conical centering guide detachably engaged with the lower end of the cylindrical head for positioning said head within a central opening in the work being engaged. 15
15. 5. In work handling apparatus of the character described, a lifting device including a carrying member, a cylindrical head depending from the carrying member, work-gripping jaws carried by the head and horizontally movable relative thereto, hydraulically operated means for projecting the jaws including a piston and cylinder in the head for each jaw and fluid supply means for the cylinders carried by the carrying member, means for retracting the work-gripping jaws to their inoperative positions within the head and a ported block to which each piston is attached, said fluid supply means being in communication with said ported block, and a conical centering guide detachably engaged with the lower end of the cylindrical head for positioning said head within a central opening in the work being engaged. 20
20. 6. In work handling apparatus of the character described, a lifting device including a carrying member, a cylindrical head depending from the carrying member, work-gripping jaws carried by the head and horizontally movable relative thereto, hydraulically operated means for projecting the jaws including a piston and cylinder in the head for each jaw and fluid supply means for the cylinders carried by the carrying member, means for retracting the work-gripping jaws to their inoperative positions within the head, the fluid supply means supported on the carrying member including a fluid pump, an overrunning motor for operating the pump, a pipe line connection between the pump and each piston, a non-return check valve in said pipe line, a by-pass pipe connected at its ends to said pipe line at opposite sides of said check valve and a normally spring-closed hand-operated valve in the by-pass pipe. 25
25. 7. In work handling apparatus, a carrying member, a tubular head depending therefrom, work-gripping jaws adapted for engagement interiorly of tubular work carried normally interiorly of said tubular head and movable transversely of said head for projection laterally thereof into work engaging positions and controlled fluid operated means for projecting the jaws into work engaging positions, the fluid operated means being of hydraulic character and including a fluid pump and operating motor therefor mounted on the carrying member, a ported block mounted in the tubular head, cylinder and piston connections between said block and gripping jaws, a pipe connection between the pump and ported block having a check valve therein opening toward the block and a by-pass pipe connected to the aforesaid pipe at opposite sides of said check valve and having a manually controlled valve therein to permit the return of fluid from the ported block to said pump for the retraction of the gripping jaws. 30
30. 8. In work handling apparatus, a carrying member, a tubular head depending therefrom, work-gripping jaws adapted for engagement interiorly of tubular work carried normally interiorly of said tubular head and movable transversely of said head for projection laterally thereof into work engaging positions and controlled fluid operated means supported on the carrying member and head for projecting the jaws into work engaging positions, the fluid operated means being of hydraulic character and including a fluid pump and operating motor therefor mounted on the carrying member, a ported block mounted in the tubular head, cylinder and piston connections between said block and gripping jaws, a pipe connection between the pump and ported block having a check valve therein opening toward the block and a by-pass pipe connected to the aforesaid pipe at opposite sides of said check valve and having a manually controlled valve therein to permit the return of fluid from the ported block to said pump for the retraction of the gripping jaws. 35
35. 9. In work handling apparatus of the character described, a lifting device including a carrying member, a cylindrical head depending from the carrying member, work-gripping jaws carried by the head and horizontally movable relative thereto, hydraulically operated means for projecting the jaws including a piston and cylinder in the head for each jaw and fluid supply means for the cylinders carried by the carrying member, means for retracting the work-gripping jaws to their inoperative positions within the head and a ported block to which each piston is attached, said fluid supply means being in communication with said ported block, and a conical centering guide detachably engaged with the lower end of the cylindrical head for positioning said head within a central opening in the work being engaged. 40
40. 10. In work handling apparatus of the character described, a lifting device including a carrying member, a cylindrical head depending from the carrying member, work-gripping jaws carried by the head and horizontally movable relative thereto, hydraulically operated means for projecting the jaws including a piston and cylinder in the head for each jaw and fluid supply means for the cylinders carried by the carrying member, means for retracting the work-gripping jaws to their inoperative positions within the head and a ported block to which each piston is attached, said fluid supply means being in communication with said ported block, and a conical centering guide detachably engaged with the lower end of the cylindrical head for positioning said head within a central opening in the work being engaged. 45
45. 11. In work handling apparatus of the character described, a lifting device including a carrying member, a cylindrical head depending from the carrying member, work-gripping jaws carried by the head and horizontally movable relative thereto, hydraulically operated means for projecting the jaws including a piston and cylinder in the head for each jaw and fluid supply means for the cylinders carried by the carrying member, means for retracting the work-gripping jaws to their inoperative positions within the head and a ported block to which each piston is attached, said fluid supply means being in communication with said ported block, and a conical centering guide detachably engaged with the lower end of the cylindrical head for positioning said head within a central opening in the work being engaged. 50
50. 12. In work handling apparatus of the character described, a lifting device including a carrying member, a cylindrical head depending from the carrying member, work-gripping jaws carried by the head and horizontally movable relative thereto, hydraulically operated means for projecting the jaws including a piston and cylinder in the head for each jaw and fluid supply means for the cylinders carried by the carrying member, means for retracting the work-gripping jaws to their inoperative positions within the head and a ported block to which each piston is attached, said fluid supply means being in communication with said ported block, and a conical centering guide detachably engaged with the lower end of the cylindrical head for positioning said head within a central opening in the work being engaged. 55

CHARLES A. SHAFFER.
